CLAIM

The ornamental design for a urine container for female patient, as shown and described.

DESCRIPTION

FIG. 1 is a perspective view of a urine container for female patients showing my new design;

FIG. 2 is a side elevational view thereof;

FIG. 3 is a side elevational view thereof, opposite that shown in FIG. 2;

FIG. 4 is a front elevational view thereof;

FIG. 5 is rear elevational view thereof; and,

FIG. 6 is a bottom plan view thereof.
